EVAPORATIVE COOLER CONSTRUCTION
Adam D. Goettl and John M. Goettl, Phoenix, Ariz.,
assignors to McGraw-Edison Company, Milwaukee,
Wis., a corporation of Delaware

Filed July 1, 1963, Ser. No. 292,021
4 Claims. (Cl. 261—74)

This invention relates to an evaporative cooler construction and more particularly to a very economical evaporative cooler construction which may be produced in great volume at a low cost to the consumer and which, therefore, provides substantial economic advantages to the general public.

Evaporative coolers are a very important item to the comfort of the general public in numerous arid regions throughout the world and in many places these coolers have become a necessity to the health of the general public. Due to the wide spread demand for evaporative coolers and due to their beneficial operation, it has been recognized that the production of a very economical evaporative cooler, to be sold at a very low cost, will permit more people to enjoy the benefits of evaporative cooling in arid regions.

Additionally, such economical evaporative coolers may attain more wide spread use in industry to provide comfort for workers, and thereby, increase production in various industries.

Accordingly, it is an object of the invention to provide a very economical evaporative cooler which will promote the wide spread use of evaporative coolers, and, thereby attain wide spread evaporative cooling benefits which will not only improve healthful conditions in homes, but in industrial establishments as well.

Another object of the invention is to provide an evaporative cooler construction which includes features contributing to low material and production costs to thereby permit a manufacturer to deliver and sell evaporative coolers at a very low cost.

Another object of the invention is to provide an evaporative cooler having a sump pan and side frame structure all formed of a single piece of sheet metal and integral with each other.

Another object of the invention is to provide a novel evaporative cooler structure wherein a sump pan and a side frame element are integral with each other and formed of a single sheet of metal, and, wherein, novel means is provided for the folding of the corners of the sump pan and the side frame member to provide a leak proof corner and yet form these members integral with each other and of a single sheet of metal.

Another object of the invention is to provide a very economical evaporative cooler construction which very admirably lends itself to machine production with a minimum amount of labor.

Another object of the invention is to provide an evaporative cooler construction having novel means in the sheet metal blank thereof for promoting accurate folding of corners of a leak proof sump pan from a single sheet of metal and maintaining the sump pan integral with a side frame portion of the evaporative cooler.

Further objects and advantages of the invention may be apparent from the following specification, appended claims and accompanying drawings, in which:

FIG. 1 is a fragmentary side elevational view of an evaporative cooler construction in accordance with the present invention and showing portions further broken away and in section to amplify the illustration;

FIG. 2 is a view of a flat sheet metal blank used to form a sump pan and side frame member of the evaporative cooler construction in accordance with the invention;

2

FIG. 3 is a sectional view taken from the line 3—3 of FIG. 2;

FIG. 4 is an enlarged fragmentary sectional view taken from the line 4—4 of FIG. 2;

5 FIG. 5 is a fragmentary side elevational view of a modified form of a folding corner structure of a blank similar to that shown in FIG. 2; and

10 FIG. 6 is a fragmentary edge elevational view of a corner of the blank shown in FIG. 5 and taken from the line 6—6 of FIG. 5.

15 As shown in FIGS. 1 and 2, an evaporative cooler sump pan and frame side member is formed of a single sheet of metal and is readily adapted to production by a machine, thereby, saving considerable labor and materials.

20 As shown in FIG. 2 of the drawings, a blank 10 is sheared out of a single sheet of metal in order to provide a sump pan blank section 12 and a side frame blank section 14. At the corners of the sump pan blank section 12 there are provided elongated indented portions 16 and 17 having ends which terminate along a line 18 which is at substantially 45 degrees to the edges 20 and 22 of the blank which terminate at the respective corner.

25 Adjacent ends of the indented portions 16 and 17 are offset to permit the portions 16 to fold into positions between the portions 17 and the general cross-section of these indented portions 16 and 17 is similar and as shown in FIG. 4 of the drawings. These indented portions 16 and 17 increase the section of the sheet metal blank and are dis-

30 posed longitudinally at right angles to the break lines 18 which are disposed at substantially at 45 degrees to the corners being formed. The groups of these indented portions 16 and 17 are substantially parallel with each other and terminate at intersections 24 of break lines 26, 28, 30 and 32 about which the metal is broken at right angles to form a sump pan bottom and three sides 34, 36 and 38.

35 It will be understood that the indented portions 16 and 17 increase the section of the sheet metal blank adjacent to the break lines, such that metal will bend precisely on the break lines adjacent the ends of the indented portions 16 and 17, which terminate at an angle to the break lines.

These three sides are also integral with the frame side break portion 14 which is formed upwardly about the break line 28 as indicated in FIG. 1 of the drawings. Additionally, break lines 38 and 40 meet the junctures 24 of the break line 28 with the break lines 26 and 30. Outwardly of the break lines 38 and 40 are flange forming portions 42 and 44 which are formed into respective flanges 46 and 48 integral with the frame blank portion 14.

45 50 The blank portion 14 is provided with an opening 50 at which an outlet 52 of a centrifugal blower 54 is connected. This blower is internally disposed relative to the evaporative cooler construction of the invention and is located above the sump portion 12, all as shown best in FIG. 1.

55 60 A top pan 56 is formed in a substantially inverted box shaped configuration, either by deep drawing or any other suitable means of fabrication to provide an economical top for the evaporative cooler construction and this top 56 is provided with flanges 58 which extend downwardly from a horizontal top portion 60. These flanges at 62 are spot welded to the flanges 46 and 48 and also to the blank portion 14 securely to hold the top 60 in connection with the upstanding side frame portion 14 which is integral with the sump structure hereinbefore described.

65 70 At corners of the sump 12 opposite the frame side portion 14 are frame members 64 which interconnect such corners of the sump pan and outer corners 66 of the top 60. These corner members 64 are substantially L1 shaped in cross-section and are secured by spot welds or other means designated 68 in connection with the top 60 in a

similar manner to the connection thereof with the flanges 46 and 48 and the frame side portion 14. Evaporative cooler pad frames 70 are connected in the conventional manner to the flanges 46 and 48 and between the corner member 64 so that the blower 54 may force air through evaporative cooler pads in the louvered frames 70 and outwardly through the outlet 52. The sump pan formed as hereinbefore described contains water which is recirculated through the pads of the pad frames 70.

It will be appreciated by those skilled in the art that the top 56 may be very economically produced to be secured in connection with the remaining structure of the evaporative cooler since any method for making the top may be used and the top need not be water proof since it does not contain water. However, the sump pan integral with the side frame portion 14 must be water proof or leak proof at the corners of the structure and yet this entire structure of the sump pan and the side frame must be formed of a single sheet of metal and preferably made by an automatic machine in order to promote economy in the manufacture of evaporative coolers.

In the modification as shown in FIG. 5, a modified means is shown for forming the break lines in the corners of the blank of sheet metal disclosed in FIG. 2. As shown in FIGS. 5 and 6 indented or creased portions 72 and 74 are in alignment with the break lines 30 and 32 respectively, while another indented portion 76 is directed in substantially the same direction as the break lines 18 hereinbefore described to induce the corner structure of the blank to fold on the line 18, and, thus, each corner of the blank is prepared according to this modification with the creased portions 72, 74 and 76 to induce the corners to fold precisely so that the sump pan structure and frame side structure may be formed integrally and provide a precisely formed sump pan structure having folded corners which are water proof and leak proof.

It will be obvious to those skilled in the art that various modifications of the present invention may be resorted to in a manner limited only by a just interpretation of the following claims.

We claim:

1. In an evaporative cooler construction the combination of: a rectangular box shaped sump pan having a bottom and two opposed pairs of upstanding sides; a frame side portion integral with one of said upstanding sides; two flange portions of said frame side portion substantially contiguous to an opposed pair of said upstanding sides of said sump pan portion, said frame side portion and said flange portions extending a considerable distance above said upstanding sides; and angularly folded portions integral with said upstanding sides and said flange portions; said folded portions disposed and extending upwardly at an angle relative to said upstanding sides and said frame side portion and to an elevation above a liquid containing level in said sump pan; a separate rectangular inverted box shaped evaporative cooler top structure coupled to said frame side portion and disposed in opposed relation with said sump pan and vertically superimposed thereover; said angularly folded portions having elongated indented portions angularly disposed to break lines of said folded portions whereby precise folding of said folded portions is accomplished when constructing the sump pan and frame side portions in integral relationship with each other and during the forming of a sump pan with sides integral with flange portions of the frame side portions.

2. In an evaporative cooler construction the combination of: a rectangular box shaped sump pan having a bottom and two opposed pairs of upstanding sides; a frame side portion integral with one of said upstanding sides; two flange portions of said frame side portion substantially contiguous to an opposed pair of said upstanding sides of said sump pan portion, said frame side portion and said flange portions extending a considerable distance

above said upstanding sides; and angularly folded portions integral with said upstanding sides and said flange portions; said folded portions disposed and extending upwardly at an angle relative to said upstanding sides and said frame side portion and to an elevation above a liquid containing level in said sump pan; a separate rectangular inverted box shaped evaporative cooler top structure coupled to said frame side portion and disposed in opposed relation with said sump pan and vertically superimposed thereover; said frame side portion and said sump pan integral with each other and formed of a single sheet of metal; indented portions of said sheet of metal at corners thereof disposed along and in alignment with break lines of said angularly folded portions precisely to initiate folding of said angularly folded portions precisely to accomplish integral folded structure between said integral frame side portion and said sump pan portion and the respective sides of the pan and the flange portions of the frame portion.

3. In an evaporative cooler construction the combination of: a rectangular box shaped sump pan having a bottom and two opposed pairs of upstanding sides; a frame side portion integral with one of said upstanding sides; two flange portions of said frame side portion substantially contiguous to an opposed pair of said upstanding sides of said sump pan portion, said frame side portion and said flange portions extending a considerable distance above said upstanding sides; and angularly folded portions integral with said upstanding sides and said flange portions; said folded portions disposed and extending upwardly at an angle relative to said upstanding sides and said frame side portion and to an elevation above a liquid containing level in said sump pan; a separate rectangular inverted box shaped evaporative cooler top structure coupled to said frame side portion and disposed in opposed relation with said sump pan and vertically superimposed thereover; said angularly folded portions having elongated indented portions angularly disposed to break lines of said folded portions whereby precise folding of said folded portions is accomplished when constructing the sump pan and frame side portion in integral relationship with each other and during the forming of a sump pan with sides integral with flange portions of the frame side portion; a plurality of said elongated indented portions having ends terminating at an angle to break line portions of said folded portions at each side of said break line portions.

4. In an evaporative cooler construction the combination of: a rectangular box shaped sump pan having a bottom and two opposed pairs of upstanding sides; a frame side portion integral with one of said upstanding sides; two flange portions of said frame side portion substantially contiguous to an opposed pair of said upstanding sides of said sump pan portion, said frame side portion and said flange portions extending a considerable distance above said upstanding sides; and angularly folded portions integral with said upstanding sides and said flange portions; said folded portions disposed and extending upwardly at an angle relative to said upstanding sides and said frame side portion and to an elevation above a liquid containing level in said sump pan; a separate rectangular inverted box shaped evaporative cooler top structure coupled to said frame side portion and disposed in opposed relation with said sump pan and vertically superimposed thereover; said angularly folded portions having elongated indented portions angularly disposed to break lines of said folded portions whereby precise folding of said folded portions is accomplished when constructing the sump pan and frame side portion in integral relationship with each other and during the forming of a sump pan with sides integral with flange portions of the frame side portion; a plurality of said elongated indented portions having ends terminating at an angle to break line portions of said folded portions at each side of said break line portions; indented portions at one side

of a respective break line portion being parallel to and in offset relation to said indented portions at an opposite side of said break line portion, whereby, folding of said angularly folded portions disposes said offset indented portions between the other of said indented portions. 5
